The ornamental design for a piano, as shown and described.

DESCRIPTION

FIG. 1 is a perspective view of the front, top and right of a piano according to our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is an enlarged view at 8-8 line thereof in FIG. 7.

The elements shown in broken lines are for illustrative purposes only and form no part of the claimed design.
